UNITED STATES PATENT OFFICE.

JOHN H. SCHROEDER AND CARSON D. BAUCOM, OF SAVANNAH, GEORGIA.

ELECTRICAL TRAIN-CONTROLLING SYSTEM.

1,104,279.

Specification of Letters Patent.

Patented July 21, 1914.

Application filed November 5, 1913. Serial No. 799,334.

To all whom it may concern:

Be it known that we, JOHN H. SCHROEDER and CARSON D. BAUCOM, of Savannah, in the county of Chatham and State of Georgia, have invented certain new and useful Improvements in Electrical Train-Controlling Systems; and we do hereby declare the following to be a full, clear, and exact description of the invention, such as will enable others skilled in the art to which it appertains to make and use the same.

This invention relates to improvements in electrical train controlling systems, and more particularly to such as are constructed and adapted for use in a system of overlapping railway blocks for automatically controlling the progress of trains,—the object of the invention being to provide simple and efficient circuits and devices whereby trains will be prevented from entering a block from either end when another train occupies the block,—thus protecting the train against both head-on and rear-end collisions.

With this object in view, the invention consists in certain novel features of construction and combinations of parts as herein-after set forth and pointed out in the claims.

In the accompanying drawings, Figure 1 is a diagrammatical view illustrating the circuits and devices along the railroad; Figure 2 is a view showing the cab devices, and Figs. 3, 4 and 5 are enlarged views of one of the mechanical switches or circuit shifting devices to be operated by a passing train.

Figure 1 represents the track of a section of railway which latter is, for the purpose of our invention divided into blocks and the several blocks are so arranged that they overlap,—one series of blocks, for example, extending from A to B and the other series of blocks alternating with the blocks of the first series and each extending from C to D.

At respective ends of each block, contact devices or ramps 2 are located and the ramps at respective ends of each block are connected by a conductor 3, two ramps being located at each block junction, one connected by a conductor 3 with a ramp at the opposite end of a block in one direction and the other connected by a conductor 3 with a ramp at the opposite end of a block in the opposite direction. The connections of the ramps for the blocks A—B are separate from the electrical connections between the ramps

of the alternating or overlapping blocks C—D as clearly illustrated in Fig. 1 of the drawing.

The ramps 2 may be supported by poles or overhead structures in position to be engaged by trolley wheels or shoes (not shown) on the rolling equipment so as to complete circuits (as hereinafter explained) for controlling the operation of devices on the said rolling equipment,—or said ramps might be located adjacent to the rails to be engaged by suitably arranged shoes or collectors.

A feed wire 4, connected with any suitable source of electric energy, extends along the railway and at one end of each block, this feed or supply wire is connected, by a conductor 5, with one terminal of a solenoid coil 6,—the other terminal of this coil being connected, by a conductor 7, with the contacts 8—9 of a mechanically operated switch 10 located at one end of a block. This switch is operable by the wheels of or shoes on the rolling equipment, for which purpose, a depressible rail 11^a is located near the railway rail at a block terminal and connected with said switch. The construction of the mechanically operated switches will be more fully hereinafter described. The switch 10 is provided also with contacts 11—12 and 85 a switch arm 13 is provided, to be operable when the rail 11 is depressed,—said switch arm being adapted to electrically connect the contacts 8—11 or the contacts 9—12. A mechanically operable switch 14 identical in construction and operation to the switch above mentioned as being located at one end of a block, is located at the other end of the same block. The contact 11 of switch 10 at one end of a block is connected, by a conductor 15 with the contact 8 of switch 14 at the other end of the same block, and contact 12 of switch 10 is connected, by a conductor 16 with the contact 12 of switch 14. The contacts 9 and 11 of switch 14 are electrically connected and are normally grounded by a conductor 17.

Each solenoid 6 is adapted to control a normally open circuit closer 18. This circuit-closer comprises a cross-arm 19 carried by the core of the solenoid, and two contact blocks 20—21. The contact block 20 is connected, by a conductor 23 with the conductor 5, and the contact block 21 is connected by a conductor 21^a with conductor 110

3, so that when the circuit closer 18 is closed, current may be supplied to the connected contact ramps 2 at respective ends of a block.

- 5 Each mechanical switch 10 and 14 comprises a suitable framework 24 in which a shaft 25 is mounted, said shaft having the switch arm 13 secured thereto so as to connect the contacts of the switch in pairs. A clutch 10 wheel 26 is also secured to the shaft 25, and encircling this wheel, is an oscillatory clutch ring 27 having a plurality of tapering grooves 28 in its inner face for the reception of clutch balls or rollers 29 which 15 operate with the peripheral portion of the wheel 26 to turn the latter and the shaft 25 in one direction when the ring 27 is turned in one direction,—said ring being movable in the reverse direction independently of the clutch wheel. In order to retain the switch arm 13 in its normal position or in the position to which it may be shifted, springs 30 may be employed, one 20 end of each of said springs being fixed and the other end bearing against a flat face afforded by an angular portion of the shaft 25. For imparting motion to the clutch ring, when the contact rail 11 is depressed, said ring is connected with the depressible 25 contact rail by means of rod or pitmen devices. Under normal conditions, the switch arm of the mechanical switch at one end of a block will connect the contacts 9—12 while 30 the other end of the same block will connect the contacts 8—11. Thus it will be seen that the circuit of the conductors 15 and 16 will be normally open at the respective 35 mechanical switches.
- 40 Viewing the railroad as depicted in Fig. 1 of the drawing; if a train should enter the left hand end of a block, manipulation of the mechanical switch 10 by depression of the rail 11, will cause the switch arm 13 to 45 be shifted from the contacts 9—12 and caused to electrically connect the contacts 8—11. A circuit will be thus completed from the feed wire, by conductor 5 to solenoid coil 6; then by conductor 7 to contact 8 50 of mechanical switch 10; then by switch arm 13 to contact 11; then by conductor 15 to contact 8 of mechanical switch 14 at the other end of the block; then by said last-mentioned switch arm to contact 11, to contact 9 of switch 14, and finally by conductor 55 17 to the ground. The current in this circuit will energize the solenoid 6, and close the circuit closer 18,—thus closing a partial circuit from feed wire 4 to conductor 5, to conductor 23, through circuit-closer 18 to conductor 21, to conductor 3 and then to ramps 2 at respective ends of the block. It will be readily understood that if a train should enter the block from the right instead of the 60 left, the mechanical switch 14 would be

shifted so as to complete the circuit of the solenoid through the conductor 16 instead of the conductor 15.

With the conditions as above described, when a train occupies a block; should another train attempt to enter the block from either end, the trolley shoe or collector (not shown) on such train will engage a ramp 2 and thus complete the partial circuit of said ramp, through an electromagnet 31 on the rolling equipment,—said magnet being arranged to operate suitable trip devices 32 with which the valve 33 of the air brake mechanism or steam supply or both, may be connected and by means of which said valve or valves may be operated to stop the progress of the train.

Various slight changes might be made in the details of construction of our invention without departing from the spirit thereof or limiting its scope and hence we do not desire to restrict ourselves to the precise details herein set forth.

Having fully described our invention what we claim as new and desire to secure by Letters-Patent, is:

1. In an electrical train controlling system, the combination with a block of railway, a source of electrical supply, rolling equipment, and electrically controlled train controlling means on the rolling equipment, of contact ramps at respective ends of said block, to supply current to the electrically controlled devices on the rolling equipment, a normally open partial circuit connecting said ramps with the source of electrical supply, an electro-magnetically operated circuit closer in said partial circuit, circuit closing means arranged at respective ends of the block to be mechanically operated by a train, and normally open circuits including said circuit closing means, the magnet of said electro-magnetically operated circuit closer and the source of electrical supply.

2. In electrical train controlling system, the combination with a block of railroad, and a source of electrical supply, of contact ramps at respective ends of said block, a conductor connecting said ramps, a partial circuit connecting said conductor with the source of supply, a normally open circuit closer in said circuit, a solenoid for closing said circuit closer, a circuit from the source of supply and including said solenoid, and mechanically operable circuit closers at respective ends of the block for automatically closing the circuit of the solenoid when a train enters either end of the block.

3. In an electrical train controlling system, the combination with a block of railway and a source of electrical supply, of contact ramps at respective ends of the block for supplying current to electrically controlled train controlling means on rolling equipment, a conductor connecting said ramps, a

- partial circuit connecting said conductor with the source of supply, a normally open circuit-closer in said partial circuit, electro-magnetically operable means for closing said circuit closer, a normally open circuit connecting said electro-magnetically operable means with the source of supply, mechanically operable switches at respective ends of the block and both included in said normally open circuit, two conductors connecting said switches, and means operable by a train for operating said switches to close said normally open circuit through one or the other of the said two conductors.
4. In an electrical train controlling system, the combination with a block of railroad, and a supply conductor, of contact ramps at respective ends of the block, a conductor connecting said ramps, a partial circuit connecting said conductor with the source of supply, a normally open circuit closer in said partial circuit, electromagnetic controlling means for closing said circuit closer, a mechanical switch at each end of the block, each mechanical switch comprising four contacts and a switch arm to connect said contacts in pairs, a partial circuit including two contacts of one of said switches, the electro-magnetic controlling means of the circuit closer and the source of supply, a partial grounded circuit including two contacts of the other mechanical switch, two conductors connecting the remaining contacts of the respective mechanical switches, and means operable by rolling equipment for operating
- said mechanical switches to close or open the circuit of the electro-magnetic controlling means for the circuit closer.
5. In an electrical train controlling system, the combination with a block of railway, a source of electrical supply, electrically connected contact ramps at respective ends of the block, and electro-magnetically controlled means for supplying current to said ramps from the source of supply, of mechanical switches at respective ends of the block, each switch comprising four stationary contacts and a revoluble arm for connecting said contacts in pairs, a clutch connected with said arm, means operable by a train for operating said clutch to turn the switch arm, a partial circuit including two contacts of one mechanical switch and the said electro-magnetically controlled means, two contacts of the other switch being grounded, conductors connecting the remaining contacts of the respective mechanical switches, rolling equipment, and electro-magnetically controlled means on the rolling equipment to receive current from said ramps.

In testimony whereof, we have signed this specification in the presence of two subscribing witnesses.

JOHN H. SCHROEDER.
